UNITED STATES PATENT OFFICE.

WILLIAM M. WATTIE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

CONNECTER FOR LOOM HARNESS FRAMES.

Application filed August 1, 1924. Serial No. 729,640.

This invention relates to strap connecters for the harness frames of looms and an object of the invention is to provide a connecter readily adjustable lengthwise of the frame to register with the cam treadles or other harness actuating mechanism.

In looms for weaving very heavy fabric the harness frames are usually provided with spaced rods on which are mounted the heddles for the warp threads, the ends of the heddles being provided with eyes or slots through which the heddle bars extend. It is desirable that these heddle bars be as close to the adjacent parts of the frame as possible, but the connecters at present in use for heavy looms have a bolt passing through the frame bar and a nut thereon to hold the same in place. When moving the strap connecter for repairs or adjustment the nut is unscrewed toward the heddle rod, this condition requiring that the latter be spaced from the harness bar a greater distance than is desirable. Also, in looms of this type the harnesses are usually actuated by levers operated by under cams, the latter being adjustable lengthwise of the loom, and in order to align the straps with the cams in their various positions, it has heretofore been necessary to drill a series of holes through the frames.

In my present invention, I provide a connecter which surrounds the harness frame member without requiring holes therethrough and free when loosened to slide thereon to assume variously adjusted positions.

With this and other objects in view which will appear as the description proceeds, my invention resides in the combination and arrangement of parts hereinafter set forth and claimed.

In the accompanying drawings, wherein I have shown one form of my invention,

Fig. 1 is a front elevation of the harness frame having my invention applied thereto,

Fig. 2 is a detail view of the connecter in front elevation,

Fig. 3 is a top plan of the connection looking in the direction of arrow 3, Fig. 2, and,

Fig. 4 is a section taken on line 4—4 of Fig. 2.

Referring more particularly to the drawings, it will be seen that I have provided a harness frame 10 having horizontal bars 11

connected by end bars 12 and having spaced 55 heddle rods 13 between which extend the heddles 14. The bars 11 are preferably of wood and rectangular in section as shown in Fig. 4, and the harness frame may be of any 60 approved construction.

The harness frames on which my invention is used are raised and lowered by a harness motion which actuates the frames by means of straps or other flexible connections attached to the frames by connecters. My 65 present invention relates more particularly to these connecters, and in carrying out my improvements, I provide each connecter with a pair of side members 20 and 21, respectively, the lower ends of which are 70 formed substantially the same, each having a foot 22 perforated as at 23 to receive bolts 24. The upper end of member 20 has extending therefrom in opposite directions trunnions 25 which are engaged by hooks 26 75 formed on the member 21. The member 20 is provided with a pair of open slots 27 which receive the hooks 26, the inner end of the slots serving to prevent relative lateral motion of the members. 80

Extending between the feet 22 is a strap holder 28, the lower end of which is slotted as at 29 to receive the strap 30. The upper end of the connecter 28 is broadened and flattened to form a head 31 which engages 85 one of the horizontal faces 32 of the bar 11. The head 32 is formed to extend as at 33 beyond the feet 22 and has surfaces 34 on the under side thereof to correspond with surfaces 35 on the feet 22. As shown in 90 Fig. 2 the head 32 extends beyond the bolts 24 so that angular motion of the connecter is prevented, even though but one of the bolts is in place.

In applying the connecter to the frame bars the trunnions and hooks are interconnected and the members 20 and 21 closed around the bar 11, the strap holder being located between the feet 22 and so positioned that appropriately placed openings 37 therein will register with the openings 23 to receive the bolts. The latter are then positioned and tightened, the effect of which is to draw the members 20 and 21 tightly 95 against the member 11, provision for this condition being made by having the shank of the strap holder thin enough to be out of contact with the feet 22 so that the latter 100

can be drawn together and the members 20 and 21 drawn against the vertical walls of member 11 without interference by the strap holder 28.

5 I find in the manufacture of the parts that it is desired to have the surfaces 34 and 35 inclined so they may have a wedging action when drawn together to force the head 32 against the bar 11 when the bolts are 10 fastened.

From the foregoing, it will be seen that I have provided a strap connector of substantial construction which passes around the harness frame and has provision for longitudinal adjustment with respect to the harness frame. This adjustment is attained by loosening the bolts 24 without disturbing the hinged connection defined by the trunnions 25 and hooks 26. Also, the strap holder 15 is provided with a head which is forced tightly against the frame member by inclined surfaces to prevent lateral movement of the connector. Lateral movement is further prevented by sharp prongs 36 which extend from the members 20 and 21 and project into the vertical sides of the wooden bar 11, the prongs preferably being spaced as far as possible from the pivotal connection between the connector members so that said 20 connector may be moved by loosening the bolts 24 without disconnecting the trunnions 25 from hooks 26. It will also be noted that the point at which the connector is released 25 is outside the frame, thus permitting adjustments or replacements of the connector without interfering with the heddle rod.

Having described one form of my invention it will be apparent that those skilled in the art may make changes and modifications 30 therein without departing from the spirit of the invention and I do not wish to be limited to the details shown herein, but what I do claim is:

45 1. A harness connector for a loom harness frame comprising a pair of members having portions thereof interconnected to form a pivotal attachment, and means to hold the members together and clamp the same against the harness frame, said means being 50 on the opposite side of the harness member from the interconnected portions.

2. In a harness connector for a loom harness frame, a pair of connector members having 55 pivotal connection with each other on one side of a frame part, and means on the other side of the frame part to draw said members together to clamp the same against said frame part.

3. In a loom harness frame having a longitudinal member, a strap holder in engagement with one face of the longitudinal member, connector members encircling said member and having holding connection with each other, and means lying outside the member and extending through said members and 60 said strap holder to clamp said members to the longitudinal bar and position said strap member.

4. In a harness connector for loom harness frames having a longitudinal bar, a pair of 65 connector members encircling said longitudinal bar, means defining a pivotal connection between said members on one side of the longitudinal member, a strap holder located between the members on the opposite side of 70 the longitudinal bar, and means passing through said members and the strap holder to secure the same to the longitudinal bar.

5. In a harness connector for loom harness frames having a longitudinal bar, a 75 pair of separate connector members having interlocking attachment with each other on one side of the bar, a strap holder located between the members on the opposite side of 80 the bar and having a broadened head to engage a portion of the bar, and means extending transversely of the plane of the harness frame to hold said members and strap holder to the bar, said head extending on both 85 sides of said means to prevent angular motion of strap holder.

6. In a harness connector for loom harness frames having a longitudinal bar, a plurality 90 of members encircling said bar, a strap holder having connection with said encircling means, means to draw said members and said strap holder together, and coacting inclined faces formed on said members and said strap holder to force the latter against 95 the bar.

100 7. In a harness connector for loom harness frames having a longitudinal bar, a pair of connector members encircling said bar and having interlocking connection with 105 each other and having free spaced ends, a strap holder located between the said free ends of the connectors, coacting inclined faces formed on the connector members and strap holder, and means to draw said members and strap holder together, said inclined faces acting to force the strap holder against 110 the longitudinal bar.

In testimony whereof I have hereunto affixed my signature.

WILLIAM M. WATTLE
